(57) **CLAIM**

The ornamental design for a body composition meter, as shown and described.

DESCRIPTION

FIG. 1 is a perspective view from above of a body composition meter according to our novel design;

FIG. 2 is a front view of the body composition meter of FIG. 1;

FIG. 3 is a rear view of the body composition meter of FIG. 1;

FIG. 4 is a right side view of the body composition meter of FIG. 1;

FIG. 5 is a left side view of the body composition meter of FIG. 1;

FIG. 6 is a plan view of the body composition meter of FIG. 1;

FIG. 7 is a bottom view of the body composition meter of FIG. 1;

FIG. 8 is a perspective view from above of the body composition meter of FIG. 1 with a transparent section having a first degree of transparency being shaded;

FIG. 9 is a perspective view of the body composition meter of FIG. 1 with a transparent section having a second degree of transparency being shaded; and,

FIG. 10 is an enlarged plan view of the body composition meter of FIG. 1 with the display being switched on.

The broken lines in FIGS. 1, 6, 8, 9 and 10 showing a representative shape of the operating keys in the body composition meter, is for illustrative purposes only, and forms no part of the claimed design.
